UNITED STATES PATENT OFFICE

138,179

DESIGN FOR A MECHANICAL LUBRICATOR

Bengt E. Folke, Mamaroneck, N. Y., assignor to
Nathan Manufacturing Company, New York,
N. Y., a corporation of New York

Application February 28, 1944, Serial No. 112,735

Term of patent 14 years

(Cl. D46—1)

To all whom it may concern:

Be it known that I, Bengt E. Folke, a citizen of the United States and a resident of the village of Mamaroneck, in Westchester County and State of New York, have invented a new, original, and ornamental Design for Mechanical Lubricators, of which the following is a specification, reference being had to the accompanying drawing, forming a part thereof.

In the drawing,

Fig. 1 is a front elevational view of a mechanical lubricator embodying my new design;

Fig. 2 is a side elevational view of the same; and

Fig. 3 is a plan view of the same.

I claim:

The ornamental design for a mechanical lubricator, substantially as shown.

BENGTE FOLKE.
